BUILDING STRUCTURE

Robert G. Le Tourneau, Peoria, Ill., assignor to
R. G. Le Tourneau, Inc., a corporation

Application September 16, 1940, Serial No. 356,939

7 Claims. (Cl. 108—1)

This invention relates in general to an improved building structure, and in particular the invention comprises improvements in building structures which constitute an assembly of connected, prefabricated panel units or sections.

The principal object of the instant invention is to produce, in a building structure, a roof, of self-supporting dome type, made up of a multiplicity of prefabricated and metallic panel units or sections secured together in rigid relation.

Another object of the invention is to provide a dome structure, as above, wherein the separate panel sections are of predetermined configuration; each section as prefabricated bearing a predetermined relation to the circumferential and radial curvature of the dome structure.

A further object of the invention is to employ a novel form of movable, inside scaffold or "sweep" designed to facilitate erection of the dome structure, and to assure proper positioning, alignment, etc., of the prefabricated sections as the same are brought into place.

A further object of the invention is to produce a simple and inexpensive structure and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Figure 1 is a fragmentary, somewhat diagrammatic top plan view of the dome structure.

Figure 2 is a sectional elevation of a completed building embodying the improved dome structure.

Figure 3 is a side view of one of the prefabricated panel sections.

Figure 4 is an end view of one of the prefabricated panel sections.

Figure 5 is a fragmentary elevation of the movable scaffold illustrating the manner of its use to support and locate the prefabricated panel sections.

Referring now more particularly to the characters of reference on the drawings, the invention is here disclosed as embodied in an auditorium or the like of circular configuration; such auditorium comprising generally a vertical side wall 1, entry doors 2 therein, and a self-supporting dome type roof 3.

Both the side wall 1 and the dome 3 are constructed of prefabricated, metallic panel sections

which include spaced inner and outer metallic sheets 4 secured in rigid relation by tie straps or bracing struts 5; each sheet having inturned flanges 6 about its edges. In general, these panel sections are constructed in the manner shown in my issued United States Patent No. 2,180,830, dated November 21, 1939.

The circular side wall 1 is made up of a multiplicity of elongated rectangular panel sections 10 indicated generally at 7 disposed on end and with the abutting flanges 6 forming an exposed seam which is welded together; while the dome structure comprises the following assembly of panel sections indicated generally at 8.

The multiplicity of panel sections 8 forming the dome are disposed in a plurality of horizontal and circular courses 9, such courses progressively reducing in diameter from the lowermost upward, but all being the same radial width.

Each panel section 8 forming the dome is curved both circumferentially and radially to a predetermined extent; i. e., is prefabricated in the form of a small portion or segment of the sphere of which the dome forms a part. These panel sections 8 are elongated and extend lengthwise in a direction radially of the dome. Each such panel section is of substantially the same width at its lower end, but decreasing in width toward its upper end; the side edges being radial with said dome, and thus causing the joints of the different courses to be broken, as is desirable. By forming all the panel sections of substantially the same width at the lower end, prefabrication of the panels is facilitated and cost of manufacture reduced.

The panel sections as erected in course by course have the flanges thereof engaging the flanges of the adjacent sections, and such engaged flanges forming seams which are welded together exteriorly and interiorly of the dome, into rigid assembly.

It is also to be noted that the flanges 6 of all the panels are disposed in planes radially of the center of the sphere of which the dome forms a portion, whereby the sections, which are relatively deep, tend to wedge into each other when assembled.

In order to facilitate erection of the above described dome, a unique form of interior and movable scaffold or "sweep" is employed; such scaffold being shown in Fig. 5.

This scaffold comprises a central, vertical member or post 10 turnably mounted at its lower end in a supporting base 11. A truss type scaffold assembly, indicated generally at 12, radiates

in opposite directions, in clearance relation to the floor, from post 10 and terminates short of but adjacent side wall 1. The upper edge of this scaffold is of a configuration generally symmetrical to that of the dome, and is disposed in a plane relatively close to but inwardly of the plane to be occupied by the inner surface of the dome.

Panel section supporting jacks 13 are detachably mounted on and project upwardly from the scaffold in longitudinally spaced relation, as shown in Fig. 5. Each panel section is swung into approximate position by a crane (not shown), and is then exactly located by jacks 13. In order that a workman can manipulate the jacks, as well as weld the interior seams, I provide a platform 14 suspended by cables 15 from cross bars 16 on the upper portion of the scaffold. As is obvious, the scaffold will be swung about its axis as each course is being erected, and by suitable releasable connection, both jacks 13 and cross bars 16 may be moved up the scaffold as each course of the dome is completed. The parts of the scaffold are all detachably bolted together, so that said scaffold may be dismantled and withdrawn through doors 2 when the dome is finished.

From the foregoing description it will be readily seen that I have produced such a structure as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

1. A dome structure of spherical configuration comprising a plurality of circumferential courses of prefabricated panel sections, the side edges of each panel section being radial of the dome, in-turned flanges about the edges of said panel sec-

tions, the flanges of the sections engaging corresponding flanges of adjacent sections, and means securing the panel sections together.

2. A structure as in claim 1 in which said means comprises welding at the seam formed by engaged corresponding flanges of the panel sections.

3. A dome structure of spherical configuration comprising a plurality of circumferential courses of prefabricated relatively deep panel sections, in-turned peripheral flanges on the panel sections extending radially of the dome, the flanges of the sections engaging corresponding flanges of adjacent sections, and means securing adjacent sections together in rigid relation.

4. A dome structure of spherical configuration comprising a plurality of circumferential courses of prefabricated panel sections, in-turned peripheral flanges on the panel sections extending radially of the dome, the flanges of the sections engaging corresponding flanges of adjacent sections, and means securing adjacent sections together in rigid relation; each of said panel sections in all the courses being of substantially the same width at its lower end.

5. A structure as in claim 1 in which the flanges on the panel sections are disposed in planes radially of the center of the sphere of which the dome forms a portion.

6. A structure as in claim 1 in which the panel sections include inner and outer panels spaced apart a substantial distance; the flanges extending about the edges of both panels and being disposed in planes radially of the center of the sphere of which the dome forms a portion.

7. A dome of spherical configuration comprising an assembly of elongated and prefabricated relatively deep panel sections erected in edge to edge engagement; each panel section being curved both radially and circumferentially of the dome, and peripheral flanges along the edges of each panel disposed in a plane radially of the dome.

ROBERT G. LE TOURNEAU.
